UNITED STATES PATENT OFFICE.

BENJAMIN F. RITTENHOUSE, OF NORRISTOWN, PENNSYLVANIA.

MOLDING MACHINERY.

SPECIFICATION forming part of Letters Patent No. 427,708, dated May 13, 1890.

Application filed January 22, 1890. Serial No. 337,704. (No model.)

To all whom it may concern:

Be it known that I, BENJAMIN F. RITTENHOUSE, of Norristown, county of Montgomery, and State of Pennsylvania, have invented an improvement in Molding Machinery, of which the following is a specification.

My invention has reference to molding machinery; and it consists of certain improvements, which are fully set forth in the following specification and shown in the accompanying drawings, which form a part thereof.

My invention has particular reference to machines especially adapted for casting car-wheels, and embodies a construction in which the mold is formed of metal and is provided with mechanism whereby it may be rotated during the admittance of the molten metal to the mold. Furthermore, the mold is combined with a truck in such a manner that after the wheel has been cast it may be liberated from the mold and conveyed upon the truck to the rolling-mill or other apparatus for further treatment. The mold is made in several parts, which are relatively movable, so that when brought together in operative position they form a tight mold excellently adapted to receive and hold the fluid metal until it solidifies sufficiently to be self-sustaining.

While my invention is particularly adapted to the casting of car-wheels, it may nevertheless be applied to various articles.

Referring to the drawings, Figure 1 is a sectional elevation of my improved molding apparatus, taken on line $x-x$ of Fig. 2. Fig. 2 is a plan view of same. Fig. 3 is a side elevation of same, and Fig. 4 is a side elevation showing the truck in the act of conveying the cast ingot from the molding-machine to the rolling-mill.

A is the truck-frame proper, and is provided with wheels, which run upon the two rails B B. This truck supports the central part C of the mold, which is formed of metal, and is rotated by a shaft l, which connects with the gear L, arranged below the truck. The part C, being heavy, is supported upon ball-bearings c', which permits its ready rotation. The part C of the mold is provided with vertical projections c about its periphery.

Encircling the mold part C is an annular

ring portion D, which is adapted to be adjusted vertically upon the part C. The annular part D is provided with vertical grooves d, which receive the vertical projections c of the central part C, and thereby insure its being rotated with the part C during the casting operation. Arranged above the annular part D and the central part C is the cap or cover E, which is provided with a central opening F, for receiving the metal, and an annular guiding-rim e.

When the casting operation is taking place, the cap E rests upon the annular part D and rotates with it. The cap E may be raised or lowered by the vertically-movable parts G, which are provided with curved grooves g, in which the annular rim or flange e of the cap E works. These parts G are guided in vertical guides H, and are movable vertically by means of cranks O and links M, the said cranks being secured to a shaft P and rocked by a hydraulic or steam engine R and crank or arm Q, connected to the piston-rod. The annular part D is raised or lowered by means of vertically-movable arms I, carrying at their upper ends rollers i, which press against the under side of the said part D and while holding it in a raised position permit it to be readily rotated. These parts I are reciprocated vertically by means of links M and the cranks O. The construction is such that when the parts G are raised, the parts I are lowered, thereby raising the cap E entirely clear of the ingot and lowering the annular part D, so that it may rest upon the carriage, as shown in Fig. 4. When this is done, the carriage, with the ingot U, may run along the railway B and be delivered to the rolling-mill.

During the casting operation the mold is to be rotated, as before explained, and this is accomplished by making the gear L mesh with a gear L', secured to a shaft J, journaled in the pit and adapted to be rotated by a hand-wheel K or other suitable means. After the ingot is cast the carriage is run in the direction indicated by the arrow, Fig. 3, which causes its gear L to be drawn away from the gear L', leaving the latter in its fixed position.

S is a steam or water pipe leading to the engine R, and is provided with a valve T for

controlling the action of the engine. Where a hole is desired in the ingot, a core can be placed in the mold C.

I do not limit myself to the mere details of construction herein set out, as my invention comprehends the general principles employed in a machine of this class which are disclosed in this application. It is also evident that while the interior surfaces of the parts C D E are shown as shaped for a car-wheel they might be shaped for any other type of wheel or other article adapted to be made in a mold of this class.

Having now described my invention, what I claim as new, and desire to secure by Letters Patent, is—

1. A mold consisting of a rotatable central part forming the under middle portion of the mold and being of less diameter than the article to be molded, an annular part about said central part connected with it, so as to rotate with it, but with freedom of vertical movement between said parts, one of which is vertically movable with respect to the other, and a cap or cover to fit over the central part and annular part,

2. In a molding-machine, the combination of a mold consisting of a central part forming the under middle portion of the mold, being of less diameter than the diameter of the article to be molded, an annular part encircling said central part and extending upward to form the sides of the mold and movable vertically with respect to the central portion, and a removable cap or cover to fit over the central part and annular part, and means to raise and lower said annular part, whereby the cast ingot may be supported upon the central part with a portion of its surface projecting beyond said central supporting part.

3. In a molding-machine, the combination of a mold consisting of a central part forming the under middle portion of the mold and being of less diameter than the diameter of the article to be molded, an annular part encircling said central part and movable vertically with respect thereto, a removable cap or cover adapted to fit over the central part and annular part, and means to raise and lower said annular part, whereby the cast ingot may be

supported upon the central part with a portion of its surface projecting beyond said central supporting part, and means to rotate said mold during the casting operation.

4. In a molding-machine, the combination of a mold consisting of a central part forming the under middle portion of the mold, an annular part encircling said central part and movable vertically with respect thereto, and a cap or cover adapted to fit over the annular and central parts and movable vertically relative thereto, means for moving said annular part, and cap whereby the cast ingot may be supported upon the central part and be otherwise exposed for manipulation after becoming solidified, means to rotate said mold during the casting operation, and a truck supporting the annular part and central part of the mold and adapted to be run from under the cap or cover when the latter is raised.

5. In a molding-machine, the combination of a truck A, a central mold part C, supported thereby, an annular movable part D, arranged about the part C and movable vertically thereon, a vertically-movable cap E, adapted to rest upon the annular part D during the casting operation, and in which the internal surfaces of the parts C D E are formed to correspond to the shape of the article to be cast, and power devices for raising or lowering the parts D and E.

6. In a molding-machine, the combination of a truck A, a central mold part C, supported thereby, an annular movable part D, arranged about the part C and movable vertically thereon, a vertically-movable cap E, adapted to rest upon the annular part D during the casting operation, in which the internal surfaces of the parts C D E are formed to correspond to the shape of the article to be cast, power devices for raising and lowering the parts D and E, and means to rotate the mold parts during the casting operation.

In testimony of which invention I have hereunto set my hand.

BENJAMIN F. RITTENHOUSE.
